SUN HAT

Taskel Ellis, 1235 Sweetwater Road, Spring Valley,
Calif., and Per O. Larsen, 2936 Gobat Ave., La
Jolla, Calif.

Filed Apr. 22, 1963, Ser. No. 74,560

Term of patent 14 years

(Cl. D3—13)

Fig. 1

Fig. 2

Fig. 3

We claim:

The ornamental design for a sun hat, as shown.
